United States Patent Office

Des. 198,001
Patented Apr. 14, 1964

198,001

PROPELLER

Raymond L. Mulvane, Box 5266, Los Angeles 55, Calif.

Filed Mar. 2, 1962, Ser. No. 69,143

Term of patent 14 years

(Cl. D71—1)

FIG. 1

FIG. 2

FIG. 3

FIG. 4

FIG. 5

FIG. 1 is a perspective view of a propeller from the left rear showing my new design;

FIG. 2 is a front elevational thereof;

FIG. 3 is a rear elevational view thereof;

FIG. 4 is a lateral cross-section taken on line 4—4; and

FIG. 5 is a cross-section taken on line 5—5.

This application is a continuation-in-part of my earlier filed copending application Serial Number D. 64,179 which is a continuation of application Serial Number D. 60,819, now abandoned.

I claim:

The ornamental design for a propeller, as shown and described.
